DISPLAY CONTAINER OR SIMILAR ARTICLE

Albert E. Karp, 196—19 55th Ave., Flushing, N.Y.

Filed Feb. 1, 1962, Ser. No. 68,613

Term of patent 14 years

(Cl. D34—2)

FIG. 1

FIG. 2

FIG. 3

FIG. 4

FIG. 5

FIG. 1 is a front perspective view of a display container embodying my new design;

FIG. 2 is a side perspective view thereof;

FIG. 3 is a top perspective view thereof;

FIG. 4 is a rear top perspective view at a lesser angle than in FIG. 3; and

FIG. 5 is a front and side perspective view thereof taken from the top.

I claim:

The ornamental design for a display container or similar article, substantially as shown.
